(57) **CLAIM**

The ornamental design for a portion of electrical connector, as shown and described.

DESCRIPTION

FIG. 1 is a front perspective view of our new design for a portion of electrical connector;

FIG. 2 is another front perspective view thereof;

FIG. 3 is a front elevation view thereof;

FIG. 4 is a back elevation view thereof;

FIG. 5 is a right-side elevation view thereof;

FIG. 6 is a left-side elevation view thereof;

FIG. 7 is top plan view thereof;

FIG. 8 is a bottom plan view thereof; and,

FIG. 9 is a back perspective view thereof.

The broken lines in the drawings are included for the purpose of illustrating environmental subject matter and form no part of the claimed design.
